UNITED STATES PATENT OFFICE

154,976

DESIGN FOR A REFRIGERATED DISPENSING
CABINET

William McKinley Baird, Chicago, Ill.

Application September 28, 1946, Serial No. 133,645

Term of patent 14 years

(Cl. D80—11)

To all whom it may concern:

Be it known that I, William McKinley Baird, a citizen of the United States of America, residing at Chicago, in the county of Cook and State of Illinois, have invented a new, original, and ornamental Design for a Refrigerated Dispensing Cabinet, of which the following is a specification, reference being made to the accompanying drawing, forming a part thereof.

Fig. 1 is a front perspective view of a refrigerated dispensing cabinet, showing my new design and Fig. 2 is a rear perspective view thereof.

I claim:

The ornamental design for a refrigerated dispensing cabinet, substantially as shown.

WILLIAM MCKINLEY BAIRD.
